The ornamental design of a cover for beverage cans, as shown and described.

DESCRIPTION

FIG. 1 is a front perspective view of a cover for beverage cans showing my new design;
FIG. 2 is a top plan view thereof, in a closed position;
FIG. 3 is a bottom plan view of FIG. 2;
FIG. 4 is a front elevational view of FIG. 2;
FIG. 5 is a rear elevational view of FIG. 2;
FIG. 6 is a right side elevational view of FIG. 2;
FIG. 7 is a left side elevational view of FIG. 2;
FIG. 8 is a bottom plan view of the cover flap shown separately for clarity of illustration;
FIG. 9 is a side elevational view of FIG. 8;
FIG. 10 is a top plan view of FIG. 8;
FIG. 11 is a top plan view of the cover shown separately for clarity of illustration;
FIG. 12 is a bottom plan view of FIG. 11;
FIG. 13 is a front elevational view of FIG. 11;
FIG. 14 is a rear elevational view of FIG. 11;
FIG. 15 is a right side elevational view of FIG. 11; and,
FIG. 16 is a left side elevational view of FIG. 11.
